UNITED STATES PATENT OFFICE.

REUBEN JONES, OF ATLANTA, GEORGIA, ASSIGNOR OF THREE-FOURTHS TO
CHARLES A. SINDALL, OF SAME PLACE.

CAR-COUPING.

SPECIFICATION forming part of Letters Patent No. 350,061, dated September 28, 1886.

Application filed July 2, 1886. Serial No. 206,992. (No mod'l.)

To all whom it may concern:

Be it known that I, REUBEN JONES, a citizen of the United States, residing at Atlanta, in the county of Fulton and State of Georgia, have 5 invented a new and useful Car-Coupling; and I do hereby declare the following to be a full, clear, and exact description of the invention, such as will enable others skilled in the art to which it appertains to make and use the same, 10 reference being had to the accompanying drawings, and to letters or figures of reference marked thereon, which form a part of this specification.

This invention relates to that class of car- 15 couplings commonly known as "pin-and-link couplings," and has more especial reference to the improvement for which Letters Patent of the United States were granted to me on the 25th day of May, 1886, No. 342,517; and it 20 consists of improved means for operating the link-lifter and pin-lifter, and for holding the latter in position, as will be hereinafter fully described.

In the accompanying drawings, Figure I is 25 a side view of two draw-heads, mostly in section, showing the position of the parts. Fig. II is a top view showing the pin-lifter on the draw-head and the shoulders on the lugs on which the pin-lifting arm rests to hold the pin 30 up. Fig. III is a top view, and Fig. IV a side view, of the pin-lifter and contiguous parts of the draw-head, and especially the means by which the pin is sustained, if desired, when up. Fig. V is a top view of the link-lifter. 35 Fig. VI is a perspective showing one part of the draw-gear on a car, and the rock-shafts and arms for operating the same. Fig. VII is a detail showing the ends of the eye-pins that enter the pin-lifting arm.

40 In these figures, 1 is a draw-head; 2 and 3, the coupling link and pin of a draw-gear.

4 is a ball, which is provided with a recess, 5, in the draw-head.

6 is a link-lifter, on the rear end of which is 45 a downwardly-projecting lever which passes through a hole in the bottom of the draw-head, and has at its lower end an eye to which is connected the rock-shafts 7.

The pin-lifter 8 is pivoted to the lugs 9 by 50 means of the eye-pins 10, which are put in from each side, and being halved together on

their inner ends, and being provided with corresponding semicircular recesses in their longitudinally-abutting surfaces, are fastened in their places by the pin 11, which is preferably tapering for the purpose of keying them against the sides of the hole in the pin-lifting arm. The pin 11 also acts as a stop to prevent the pin being lifted out of the hole in the draw-head. The outer end of the arm 9 is connected to the pin 3 by a link, 12. It is also provided with an eye, to which is attached the end of the chain 13, which is intended to be extended to the top of the car or other convenient position from which it may be desirable to lift the pin when the operator is on the car. On the inner side of the lugs 9 are the shoulders 14 to sustain the link-lifter, as will be hereinafter described.

To the eye-pins 10, by which the pin-lifting arm is pivoted, are connected by eyes the rock-shafts 15, having levers at their outer ends, by means of which the pin is controlled from a position at the side of the car. The rock-shafts 15 and 7 are journaled near their outer 75 ends, the preferable way being, when the construction of the car will admit, by eyebolts screwed into the projecting sills. The draw-head is provided with a flat surface to abut against the dead-block 16, for the purpose of 80 receiving the shock of the concussion of the draw-heads.

On account of the diversity of forms in which draw-heads are constructed, sometimes not having metal at their sides in which to 85 pivot the link-lifter, I have devised this method of pivoting—namely, by a downwardly-projecting lever, which can be applied to all forms of draw-heads, and which also provides for the connecting rock-shafts from the link-lifter to the lever, passing under the projecting timbers of the car. It is also found that as pin-lifters are usually constructed and attached to the body of the car they cannot be readily adapted to flat cars, and in any case 90 do not perform their functions properly on account of the varying distance the draw-head is from the end of the car at different times.

It is often desirable to push a car, but not to couple to it. I have therefore provided shoulders on the lugs 9 by recessing the lugs on the inner sides, by reason of which the pin-lifting 100

arm, on being raised slightly higher than is required for any other purpose, has lateral play, and may be forced by either pushing or pulling on the rock-shafts 15 onto either of these shoulders. The pin 11 projects on the rear end sufficiently to prevent the pin being entirely withdrawn by abutting on the upright flange 17, as shown in Fig. IV.

Referring to my former patent, No. 342,517, the operation of coupling and uncoupling cars provided with this device is similar, except that in this the coupling-pin may be sustained in a raised position, if so desired, and the pin may be manipulated from a position on the car by means of the chain 13, and the manner of connecting the operating-handle at the corner of the car with the link-lifting apparatus is different, and on many accounts better, as is also the arrangement of the pin-lifter on the draw-head, for reasons already stated.

What, therefore, I claim as new, and desire to secure by Letters Patent of the United States, is—

1. In the draw-gear of a railway-car, the combination of the draw-head, coupling pin and link, with a **U**-shaped link-lifter, having

at its rear end a downwardly-projecting lever connected by rock-shafts with actuating-levers at the sides of the car, substantially as shown and described.

2. In the draw-gear of a railway-car, the combination of a coupling pin and link with a draw-head provided with lugs 9, having shoulders 13, the pivoted arm and link connecting it with the coupling-pin, and the rock-shafts 15, substantially as shown and described, and for the purpose specified.

3. In the draw-gear of a railway-car, the combination of the draw-heads 1, coupling pins and links 2 and 3, the balls 4, the link-lifters 6, having downwardly-projecting levers 18, and rock-shafts 7, the pin-lifting arm 8, the rock-shafts 15, and the pin 11 to prevent the withdrawal of the coupling-pin, all arranged substantially as described and shown, and for the purpose specified.

In testimony whereof I affix my signature in presence of two witnesses.

REUBEN JONES.
